UNITED STATES PATENT OFFICE

98,780

DESIGN FOR A STORE FRONT

Arthur Rosenberg, New York, N. Y., assignor to Daniels Hats, Inc., New York, N. Y.

Application August 30, 1935, Serial No. 58,377

Term of patent 14 years

To all whom it may concern:

Be it known that I, Arthur Rosenberg, a citizen of the United States, residing at New York city, in the county of New York and State of New York, have invented a new, original, and ornamental Design for a Store Front, of which the following is a specification, reference being had to the accompanying drawing, forming part thereof.

The back of the store front is plain.

I claim:—

The ornamental design for a store front as shown and described.

ARTHUR ROSENBERG.
